CLAIM

The ornamental design of a soup chafer, as shown and described.

DESCRIPTION

The present application is related to commonly-assigned U.S. Design patent application Ser. No. 29/378,379, entitled "Chafing Dish," U.S. Design patent application Ser. No. 29/378,381, entitled "Chafing Dish Frame," U.S. Design patent application Ser. No. 29/378,383, entitled "Chafer Griddle," and U.S. Design patent application Ser. No. 29/378,385, entitled "Chafer Wok," which are filed concurrently herewith and which are incorporated by reference herein in their entireties for all purposes.

FIG. 1 shows a perspective view of a soup chafer showing a first embodiment of our design;

FIG. 2 shows a front elevation view of the soup chafer of FIG. 1;

FIG. 3 shows a right side elevation view of the soup chafer of FIG. 1;

FIG. 4 shows a rear elevation view of the soup chafer of FIG. 1;

FIG. 5 shows a left side elevation view of the soup chafer of FIG. 1;

FIG. 6 shows a top plan view of the soup chafer of FIG. 1;

FIG. 7 shows a bottom plan view of the soup chafer of FIG. 1;

FIG. 8 shows a perspective view of a soup chafer showing a second embodiment of our design;

FIG. 9 shows a front elevation view of the soup chafer of FIG. 8;

FIG. 10 shows a right side elevation view of the soup chafer of FIG. 8;

FIG. 11 shows a rear elevation of the soup chafer of FIG. 8;

FIG. 12 shows a left side elevation view of the soup chafer of FIG. 8;

FIG. 13 shows a top plan view of the soup chafer of FIG. 8; and,

FIG. 14 shows a bottom plan view of the soup chafer of FIG. 8.

The broken lines are included for the purpose of illustrating portions of the soup chafer that form no part of the claimed design.
